UNITED STATES PATENT OFFICE.

ROBERT THOMPSON, OF HOLYOKE, MASSACHUSETTS.

LOCKING DEVICE FOR THE SHIPPER MECHANISM OF ELEVATORS.

SPECIFICATION forming part of Letters Patent No. 735,620, dated August 4, 1903.

Application filed April 22, 1903. Serial No. 153,780. (No model.)

To all whom it may concern:

Be it known that I, ROBERT THOMPSON, a citizen of the United States of America, and a resident of Holyoke, in the county of Hampden and State of Massachusetts, have invented certain new and useful Improvements in Locking Devices for the Shipper Mechanism of Elevators, of which the following is a full, clear, and exact description.

10 This invention relates to safety devices for elevators, more particularly for freight-elevators in mills and factories.

The invention pertains to devices combined with the shipper bar or rod which changes 15 the position of the belt or belts from the loose to the fixed pulley and which controls the action of the hoisting means for the elevator which are operative when the elevator is stopped at a floor and the belt is on the loose 20 pulley, whereby the elevator will neither be raised nor lowered, for locking the shipper-bar, so that the conditions must be continued safe and so that the shipper-bar may not be moved to establish conditions for raising or 25 lowering the elevator except as it is intentionally released by reason of positively-applied force to actuate the shipper-bar-locking devices.

The invention consists in the combination 30 or arrangement of devices and in the construction of certain of the parts, all substantially as hereinafter described, and set forth in the claims.

In the drawings, Figure 1 shows in sectional elevation an elevator, parts of floors having hoistways, the usual shipper mechanism, and the novel safety-lock for the latter. Fig. 2 is an elevation of parts comprised 35 in the safety-lock mechanism as seen at right angles to the showing thereof in Fig. 1 and as seen looking beyond the line 22 in the direction of the arrow. Fig. 3 is a plan and horizontal sectional view as taken on the line 33, Fig. 2. Fig. 4 is a somewhat-enlarged 40 sectional view in detail as taken on the line 44, Fig. 1.

Similar characters of reference indicate corresponding parts in all of the views.

In the drawings, A represents the elevator, 45 having the usual hoist-cable a , understood as having connection with a hoist-drum or "crab," the hoist arrangements being con-

trolled by the shipping devices of the usual character—such as fixed pulley b , loose pulleys d , open and cross belts e , shipper-forks f , carried on the horizontal shipper-bar B , suitably supported and guided, the shipper-bar having its endwise movement imparted to it through means of the shipper-rod g , having connection g^2 with rock-shaft g^3 , 55 which is provided with the lever g^4 , linked to the shipper-bar.

The shipper-bar B has within its upper edge a notch i , in which engages a dog j , which is carried at the extremity of a substantially 60 horizontal lever k , which is intermediately pivoted at l in a suitable bracket m and which lever at its end opposite from that at which the dog j is located has the vertically-elongated aperture n , in which engages for an advantageous degree of lost motion a rod o , 65 which in the present instance is shown as constituting, together with the vertical release-rod o^2 , (which has a degree of vertical reciprocation in the same manner as the shipper-rod,) the means for actuating to unlock the 70 shipper-bar-locking device. The aforementioned intermediately-pivoted lever k has its end at which the dog is carried balanced between the spiral springs t at opposite sides 75 thereof. The horizontal cross member u , provided with downwardly-extending ear-lugs u^2 , through which extends the horizontal rod v and about an intermediate part of which rod v the locking-dog j , which has a round 80 hole through it, as shown in Figs. 4 and 3, engages for a degree of sliding movement along the line of the rod, the spiral springs t , interposed between the ear-lugs u^2 of the dog-carrying lever and the opposite faces of 85 the dog, maintaining the latter normally balanced midway between the ends of the rod v . The dog is kept from turning because of the squared formation of its upper end, which lies closely under the extremity of the carrying member u , as will be clearly perceived on 90 reference to Fig. 4.

The device is shown in the drawings as locked in the notch i of the shipper-bar B , the position of the bar such that the forks f hold the belts on the loose pulleys at either 95 side of the fixed pulley. Now in case it is desired to move the shipper-bar to place either of the belts on the fixed pulley, so that

the elevator will be raised or lowered, the operator will first be compelled to endwise move the release-rod o^2 , as may be done by pressing downwardly with the foot against one of the steps o^3 thereof, whereupon the lever k will have its one end depressed and its opposite end, carrying the dog, elevated against the reaction of the retracting-spring w , (which is applied between an extension m^2 of the bracket m and the upper edge of the arm of the lever k , carrying the dog,) resulting in disconnecting the dog from its engagement with the shipper-bar, leaving the latter to be operated, through means of the shipper-rod g or whatever connections therefor are employed, to move one or the other of the belts onto the fixed pulley b .

5 Findicates the location of a usual and well-known form of friction device for the shipper-bar, the same constituting no part of this invention and requiring no description herein.

10 In setting up the apparatus it will be found most practical to have the range of movement of the shipper-bar from either of its positions for holding the belts on the fixed pulley to those for holding the belts on the loose pulleys such that the notched portion of the bar will come to or move slightly by the normal plane of the locking-dog j , so that there will be the certainty of the locking engagement between the dog and the shipper-bar when the latter should be in the belt-unshipping position, and any inequality or excess 15 of motion of the shipper-bar in being dropped to the unshipping position will be compensated for by the bodily-sliding movement of the dog relatively to its carrying part, and inasmuch as the vertical release-rod is usually intended to be spring-supported at the base of the building in the similar manner that the shipper-rods g for elevators are usually supported, with more or less liability of the spring for the release-rod to react upwardly somewhat unequally and also possibly after awhile to settle slightly, permitting the release-rod to sag. The provision of the vertically-elongated aperture n , in which the release-rod branch or extension o engages, is a measure to practicability, as manifest, insuring that any settling of the release-rod will be non-effective to accidentally disengage the dog from the shipper-bar, and, on the other hand, relieving the dog from undue downward pressure as might be imparted by the supporting stress ever present to the release-rod, it being manifest that the certainty of engagement of the dog is insured by the provision of the spring w , and the tension of this spring may be rendered of the utmost fitness to its purpose by the adjustable tensioning-bolt x , to which the jam and locking nuts y are applied thereabout next above the bracket extension m^2 .

20 65 The carrying-lever k may have its dog-releasing movement imparted thereto by any medium of connection appropriate therefor,

the vertical release-rod and its connections shown being operative, satisfactory, and available in most situations, and various departures and changes may be made in the details of the construction of this new device without departing from my actual invention.

70 I claim—

1. In a locking device for the shipper mechanism for an elevator, the combination with the reciprocating shipper-bar, having a socket, of a lever, a dog mounted on said lever and movable bodily therewith and having an independent sliding movement relatively thereto in a line right angular to the plane of swinging movement of the lever, springs in compression and reacting against the dog at opposite sides thereof, and means for swinging the lever for the purposes set forth. 75

2. In a device of the character described, the combination with the shipper-bar having a socket and the fixed bracket m , of the lever k intermediately pivotally hung in the bracket and having at one extremity the vertically-elongated aperture n , the release-rod o^2 having the transverse extension-rod o engaging in said aperture, a dog carried at the opposite extremity of the lever and a spring reacting against the lever to force the dog toward the shipper-bar. 80

3. In a device of the character described, the combination with the shipper-bar having the notch or socket i , of a lever having at its extremity the separated depending ear-lugs u^2 , a rod supported thereby, the dog having a hole therethrough and adapted for a sliding engagement on the rod, spiral springs encircling the rod and in compression at either side of, and between, the dog and the said ear-lugs, a spring for forcing the dog-carrying end of the lever toward the shipper-bar and means for swinging the lever. 85

4. In a device of the character described, in combination, the shipper-bar having the notch i in its upper edge and the bracket m having the bracket extension m^2 , of the lever k intermediately pivoted to the bracket, and having at its extremity the separated depending ear-lugs u^2 , the rod v horizontally supported by, and between, said ear-lugs, the locking-dog, perforated and engaging about the rod, the spiral springs t in compression at either side of the locking-dogs, the spiral spring w applied for reaction against the upper edge of the lever, a tensioning-bolt screw-engaging through the bracket extension and constituting an abutment for said spring and means for imparting a swinging movement to the lever substantially as and for the purposes set forth. 90

110 Signed by me at Springfield, Massachusetts, in presence of two subscribing witnesses.

ROBERT THOMPSON.
